C. F. GESCHICKTER

DOOR, SASH, AND SCREEN

Original Filed Dec. 24, 1925

Inventor

Charles F. Geschickter

By Jerome S. Clarkson

Attorney

UNITED STATES PATENT OFFICE.

CHARLES F. GESCHICKTER, OF WASHINGTON, DISTRICT OF COLUMBIA.

DOOR, SASH, AND SCREEN.

Application filed December 24, 1925, Serial No. 77,652. Renewed August 29, 1927.

To hang a screen door it is necessary to secure one leaf of each of the hinges of the door to the door frame, or to a strip secured to the door frame and hold said hinge in place by means of screws. The repeated hanging and taking down of screen doors greatly enlarges the screw holes making it necessary to plug them in order to give the screws a hold. Besides which, when the screen door is down the screw holes are always in view on the door frame and are unsightly. In some instances screen doors are mounted on separable spring leaves held together by the removable pintle, and in this case one-half of each hinge remains permanently on the door frame and presents a projection beyond the face of the door frame upon which one is likely to tear their clothing.

The objections related above with reference to screen doors are also present in connection with casement screens and window screens where it is desired that the screen swing on hinges for the purpose of enabling one to clean the windows.

The object of my invention is to remove these objectionable features by providing a hanging stile from which the swing member may be hung and to which the swing member can be readily attached and detached without the means of tools.

My invention consists, broadly speaking, of a hanging stile preferably U shaped in cross section, in which are secured, preferably, two hooks, one near the bottom, and one near the top of the stile on which hooks the door screen or the like is sustained in operative position. My invention consists further in providing hinges, one leaf of which is provided with a hook adapted to interengage with its corresponding hook in the hanging stile.

In the drawings:

Figure 1 is a vertical elevation (interrupted) of a frame door and hanging stile, the stile being in section embodying my invention.

Figure 2 is a top plan view of the top hinge detached.

Figure 3 is a front elevation of Figure 2.

Figure 4 is a side elevation of Figure 2.

Figure 5 is a top plan view of the lower hinge.

Figure 6 is a front elevation of the lower hinge.

Figure 7 is a side elevation of Figure 5. Figure 8 is a sectional view on the line 8—8, Figure 1.

The reference numeral 9 designates the door window or casement screen or any approved construction, and 10 the frame.

My improved hanging stile 11 is preferably U shaped in cross section, the arm 12 of the stile being longer than the arm 13 of the stile. The arm 12, as more clearly shown in Figure 8, functions as a stop for the swinging frame. The stile is provided with an upwardly extending hook 14 near its upper end and with a hook 15 near its lower end, the hook 15 projecting further toward the front of the stile than the hook 14 so that the hook 15 is in a different vertical plane from the hook 14 as clearly shown in Figure 1. These hooks are preferably formed of flat plate metal and extend substantially the full width of the hanging stile as clearly shown in Figure 8.

The hinges, according to my invention, have as usual, the two hinge leaves 16 and 17, the leaf 16 having screw holes 18 through 20 which screws are adapted to pass to secure the hinge to the door 9. The other leaf 17 of the hinge is imperforated and is longer than the leaf 16, the excess length being bent rearwardly as at 19 and then downwardly as at 20 thereby forming a hook projected from the rear face of the leaf 17 which hook is adapted to interengage with and being suspended from the hooks 14 and 15 of the stile, and when in such position connecting the door and supporting it on the hanging stile without tools and without the intervention of screws.

The lower hinge 21 is of the same construction as the upper hinge just described with the exception that the bend 22 is much shorter than the bend 19 whereby the downward bend 23 is relatively closer to its hinge leaf, the object of which is very apparent from the assembled view of Figure 1.

After the hanging stile 11 is in position, and the hinges secured to the door, the door may be hung from the hanging stile by simply passing the hooks of the hinges into the stile above the hooks and then permitting the door to move downwardly to the position shown in Figure 1 whereupon the hooks of the hinges are attached to and interengage with the hooks 14 and 15 of the hanging stile whereupon the door is simply fastened.

to the hanging stile against accidental displacement or disengagement. When so hung the door is free to swing as is usual with doors and swinging screens.

5 When it is desired to detach the door for any purpose whatever from the hanging stile it is only necessary to swing it outwardly and then lift it vertically until the hooks of the hinges are disengaged from the 10 hooks 14 and 15 of the hanging stile whereupon the door is free to be removed.

It will be noted from Figure 1 that the hooks 14 and 15 are in different vertical planes so that in the case of a sliding screen 15 the hook of the lower hinges is free to slide vertically past the upper hook 14.

I am aware that certain changes may be made in the details of construction shown herein within the scope of my invention 20 without departing from the scope of the appended claims.

What I claim is:

1. A hanging stile for doors, screens and sash, comprising a substantially U shaped 25 stile, one side member of which is longer than the other, to function as a blind stop, and hinge engaging and sustaining hooks

secured to and entirely positioned within said stile.

2. A hanging stile of the character described comprising an elongated body substantially U shaped in cross section, and hinge engaging and sustaining hooks secured within said body and positioned in different vertical planes. 30 35

3. A hanging stile of the character described comprising an elongated body substantially U shaped in cross section, and hinge engaging and sustaining hooks secured within said body, one of said hooks projecting farther toward the front of the stile than the other. 40

4. A hanging stile of the character described comprising an elongated body substantially U shaped in cross section, a hook 45 extending forwardly from the rear of the stile and upwardly, and a second hook extending from the rear of the stile a greater distance than the first named hook, both of said hooks extending upwardly and adapted 50 to be engaged by and sustain hinges.

In testimony whereof I affix my signature.

CHARLES F. GESCHICKTER.
